UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

ROCK DRILL

Application filed August 27, 1927. Serial No. 215,960.

My invention relates to rock drills.

An object of the invention is to provide improved means for supplying cleansing fluid to a hollow drill steel to aid in removing the cuttings from the hole. Another object is to provide improved means for supplementing the cleansing fluid supply by conducting a portion of the fluid to the drill steel from the rear end of the cylinder at about the time it is ready to exhaust. A more specific object is to provide means carried by the rifle bar for opening communication between the rear end of the cylinder and the drill steel when the piston is in the forward part of the cylinder and closing such communication at all other times. Other objects and advantages will, however, subsequently more fully appear.

In the accompanying drawings I have shown for purposes of illustration one form 20 which my invention may assume in practice.

In these drawings,

Fig. 1 is a central longitudinal section of parts of a typical drilling apparatus having my improved cleansing fluid supply means 25 associated therewith.

Fig. 2 is a view similar to Fig. 1 showing the moving parts in a different position.

In this illustrative embodiment I have shown my improvements associated with a 30 drilling apparatus of the pressure fluid percussive type comprising a cylinder 1 having a bore 2 in which a piston 3 is reciprocable, and adapted to actuate a drill steel 5 rotatably supported in a chuck housing 6. The rear 35 end of the cylinder is closed by a head block 7 and this head block, chuck housing and cylinder may be secured together by any suitable retaining means such as side rods 8 passing through lugs 9 on the head block, lugs 40 10 on the cylinder, and a retaining collar 11 surrounding the chuck housing and abutting against a shoulder 12. The drill steel may be automatically rotated by the well known type of rotation mechanism employing a ratchet 45 ring 13 secured in the head block, cooperating with a pawl carrier 14 and the usual pawls which are not illustrated in detail. Projecting forwardly from the pawl carrier through a bore 15 in the head block is a rifle 50 bar 16 having spiral lugs 17 formed thereon

for cooperating with spiral flutes in a rifle nut 18 in the piston 3. Preferably on the rearward stroke of the piston the rifle bar is held from rotation by means of the ratchet ring and pawl carrier, and the piston is thus rotated by the spirally grooved rotation bar and rifle nut. This rotation is transmitted through straight longitudinally extending flutes 19 in the striking bar 20, a chuck nut 21 having straight grooves 22 for cooperation with lugs 19, and a rotatable chuck sleeve 23 having lugged engagement with the drill steel 5 in the usual manner (not illustrated). As herein shown, the drilling mechanism is provided with means for supplying a cleansing medium, such as water, from a connection 24 on the head block 7, through a tube 25 extending longitudinally through the rifle bar and loosely fitting in a bore 26 in the piston 3. This tube extends through the piston and into 70 a bore 27 in the shank of the drill steel.

It has been found that a mixture of gaseous fluid with a liquid produces a more effective cleansing action and accordingly my improved drilling mechanism is provided 75 with means for conducting a portion of the fluid which is used to actuate the drilling motor to the bore in the drill steel. It is common practice to so design the longitudinally extending flutes 19 in the striking bar that 80 the same communicate with the forward end of the cylinder when the piston is in its rearward position as shown in Fig. 1. This allows a puff of the fluid which is in the cylinder to escape through the flutes 19 into the chamber 28 surrounding the shank of the drill steel and from this point it readily finds its way past a reduced extension 29 on the tube 25 into the bore of the steel. According to my invention I also provide means 85 whereby this action may be supplemented by a puff of pressure fluid from the rear end of the cylinder when the piston is in the forward part of its stroke. For this purpose the rifle bar 16 has a reduced forward extension 90 30 which is received in an intermediate bore 31 during the greater part of the piston stroke, but is of such length that it is removed into the enlarged bore as illustrated in Fig. 2 when the piston is in its forward position, 100

thus permitting communication between the enlarged chamber and the bore of the drill steel through the bores 26 and 31.

Any suitable type of fluid distribution system may be employed for distributing the motive fluid to and from the ends of the cylinder to actuate the piston. In the particular type of machine illustrated a plurality of fluid distribution valves for controlling the supply and exhaust for both ends of the cylinders are employed and since each of these valves, and the passages which they control, are similar, the description of one will suffice. The valve generally designated 32 is of the four spool differential type having enlarged spools 33 for controlling admission of fluid from the annular space 34 to the ends of the cylinder through passages 35 and 36. Motive fluid is supplied to the space 34 through a suitable connection (not shown) by way of the supply port 37. End spools 38 and 39 control the exhaust of fluid from each end of the cylinder through annular grooves 40 and exhaust ports 41. The valve is adapted to be automatically thrown from one position to another by suitable piston controlled throw passages communicating with the cylinder at 42 and 43. For a further description of this particular type of fluid distribution system reference may be had to another application Serial No. 215,958 filed by me, of even date herewith, in which application said fluid distribution means is fully disclosed and claimed. It will of course be understood, as far as the present invention is concerned, that any of the generally known types of distribution systems, either valve controlled or valveless, may be employed in the place of the one shown in the drawings.

The operation of my improved fluid cleansing supply means will doubtless be apparent from the above description and drawings, but may be briefly summarized as follows. When the piston is in the position shown in Fig. 1 and during the greater portion of its power stroke the extension 30 on the rifle bar is received within the bore 31 of the piston, thereby preventing passage of motive fluid from the cylinder through the piston. This allows the full force of the motive fluid flowing through the inlet passages to act on the piston and more effectively drive the same forwardly in its power stroke. Near the end of the stroke, however, as will be observed in Fig. 2, the extension 30 moves out of the bore 31 and allows pressure fluid in the rear end of the cylinder to escape through the rifle nut 18 around the rifle bar and through the bores 31 and 26 of the piston around the tube 25, and into the bore of the drill steel as will be obvious from the drawings. At this point gaseous fluid commingles with the water or other liquid flowing through the tube 25 and this mixture is conducted through the hollow drill steel to the bottom of the hole for

the purpose of removing the cuttings. It will be clear that if the extension 30 were omitted that motive fluid would escape around the rifle bar and through the piston during its entire stroke, thereby using an excessive amount of live pressure fluid and at the same time reducing the effective pressure on the piston and correspondingly reducing the force of the blow delivered to the drill steel. However, if this pressure is not relieved until near the end of the stroke, the force of the blow will not be materially reduced. It may also be noted that by forming the cleansing fluid supply control as a part of the rifle bar a very simple and dependable construction is obtained.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drilling mechanism, a cylinder, a hollow piston reciprocable therein, a hollow drill steel actuated thereby, means for rotating said piston and steel including a rifle bar extending from the rear end of the cylinder into the piston, and means carried by said rifle bar for controlling communication between the rear end of the cylinder and the drill steel, said means adapted to open said communication when the piston is in the forward part of its stroke, such opening being dependent solely on the position of the piston.

2. In a drilling mechanism, a cylinder, a hollow piston reciprocable therein, a hollow drill steel actuated thereby, means for rotating said piston and steel including a rifle bar extending from the rear end of the cylinder into the piston, and a rifle nut in said piston cooperating therewith in a manner to admit free passage of fluid therethrough, and means integral with said rifle bar for controlling communication between the rear end of the cylinder and the drill steel, said means adapted to admit pressure fluid from the rear end of the cylinder to the hollow drill steel when the piston is in the forward part of its stroke, such admission being controlled solely by the position of said piston.

3. In a drilling mechanism, a cylinder, a hollow piston reciprocable therein, a hollow drill steel actuated thereby, means for rotating said piston and steel including a rifle bar extending from the rear end of the cylinder into the piston, and a rifle nut in said piston cooperating therewith, said rifle bar having a portion attached thereto adapted to fit closely in a bore in said piston, and means permitting the intermittent withdrawal of

said portion from said bore to allow cleansing fluid to escape from the rear end of the cylinder through the piston when the latter is in the forward part of its stroke.

5. 4. In a drilling mechanism, a cylinder, a hollow piston reciprocable therein having a plurality of bores of different sizes, rotation mechanism including a rifle bar extending from the rear end of the cylinder into one of said bores, said rifle bar having a reduced extension attached thereto and projecting forwardly therefrom and slidably fitting in another of said bores, and means permitting the intermittent withdrawal of said extension from its bore to allow cleansing fluid to escape from the rear end of the cylinder through the piston when the latter is in the forward part of its stroke.

5. In a drilling mechanism, a cylinder, a hollow piston reciprocable therein, rotation mechanism including a rotation element operatively connected to said piston, means for supplying cleansing fluid to a hollow drill steel comprising tube means extending through said piston for continuously conducting cleansing fluid, and means for supplementing said cleansing fluid comprising a member separate from said tube means and attached to said rotation element, said member slidably fitting in a bore of said piston and adapted to be withdrawn therefrom when the piston is in the forward part of its stroke.

6. In a drilling mechanism, a cylinder, a hollow piston reciprocable therein, rotation mechanism including a rifle bar extending into the rear end of said cylinder, means for supplying cleansing fluid to a hollow drill steel comprising a tube extending through said piston for continuously conducting cleansing fluid, said piston being provided with a reduced bore loosely fitting said tube, a large bore for cooperation with said rifle bar and an intermediate bore, means attached to said rifle bar for closing said intermediate bore, and means permitting intermittent withdrawal of said closing means to supply cleansing fluid from the rear end of the cylinder to the drill steel.

7. In a drilling mechanism, a cylinder, a hollow piston reciprocable therein, a tube extending through said piston for continuously conducting a cleansing medium, rotation mechanism including a rifle bar projecting from the rear end of the cylinder into said piston, and means carried by said rifle bar and surrounding said tube for controlling communication between the rear end of the cylinder and drill steel to allow supplemental supply of cleansing fluid to flow through the piston when the latter is in the forward part of the stroke, said supplemental supply being controlled solely by the position of said piston.

8. In a drilling mechanism, a cylinder, a hollow piston reciprocable therein having a

plurality of central bores of different diameters, a tube extending through said piston and loosely fitting in the smaller of said bores for conducting a continuous supply of cleansing fluid to the drill steel, rotation mechanism including a rifle bar extending from the rear end of the cylinder into the larger of said bores, a rifle nut in said piston cooperating with said rifle bar in a manner to permit passage of fluid into said enlarged bore, a reduced projecting portion on said rifle bar surrounding said tube and slidably fitting in an intermediate bore when the piston is in the rearward portion of the cylinder and adapted to withdraw from the same into said larger bore when the piston is in the forward portion of the cylinder to allow cleansing fluid to escape from the cylinder through the piston.

9. In a drilling mechanism, a cylinder, a piston, a chuck, and means whereby reciprocation of said piston effects chuck rotation including a member carried by said cylinder and having a reduced portion having splined connection with said piston, said piston having a bore therethrough and said member having a portion cooperating with said bore to effect intermittent opening and closing of the latter.

10. In a drilling mechanism, a cylinder, a hollow piston reciprocable therein, a hollow drill steel actuated thereby, means for rotating said piston and steel including a rifle bar extending from the rear end of the cylinder into said piston, and means, including a cylindrical plug attached to the rifle bar to form a unit therewith and controlled by movement of the piston to establish communication between the rear end of the cylinder and the drill steel during certain portions of the piston travel.

In testimony whereof I affix my signature.
ELMER G. GARTIN.
